DESIGN FOR A FRONT FOR A REFRIGERATED DISPENSING CABINET

John Le Roy Remco, Wilkes-Barre, Pa.

Application March 3, 1947, Serial No. 137,296

Term of patent 14 years

(CL. D80—11)

To all whom it may concern:

Be it known that I, John Le Roy Remco, a citizen of the United States, residing at Wilkes-Barre, in the county of Luzerne and State of Pennsylvania, have invented a new, original, and ornamental Design for a Front for a Refrigerated Dispensing Cabinet, of which the following is a specification, reference being had to the accompanying drawing, forming a part thereof.

In the drawing:

Fig. 1 is a perspective view of a front for a refrigerated dispensing cabinet, showing my new design; and

Fig. 2 is a side elevational view of the same.

The rear of the cabinet is substantially plain and the side, not shown, is like the side which is illustrated.

I claim:

The ornamental design for a front for a refrigerated dispensing cabinet, as shown and described.

JOHN LE ROY REMCO.
